UNITED STATES PATENT OFFICE

102,417

DESIGN FOR AN ACCORDIONOLA

Lewis Defonso, Carnegie, Pa.

Application March 4, 1936, Serial No. 61,481

Term of patent 14 years

To all whom it may concern:

Be it known that I, Lewis Defonso, a citizen of the United States of America, residing at Carnegie, in the county of Allegheny and State of Pennsylvania, have invented a new, original, and ornamental Design for an Accordionola, of which the following is a specification, reference being had to the accompanying drawing, forming a part thereof.

I claim:—

The ornamental design for an accordionola, as shown.

LEWIS DEFONSO.
